INVENTOR
Hubert J. Braun

Charles W. Tice

UNITED STATES PATENT OFFICE.

HUBERT J. BRAUN, OF CHICAGO, ILLINOIS.

DESIGN FOR A CURTAIN TIE BACK.

Application filed October 29, 1924. Serial No. 11,209. Term of patent 14 years.

To all whom it may concern:

Be it known that I, HUBERT J. BRAUN, a citizen of the United States, residing at Chicago, Cook County, Illinois, have invented a new, original, and ornamental Design for a Curtain Tie Back, of which the following is a specification, reference being had to the accompanying drawing, forming part thereof.

I claim:

The ornamental design for a curtain tie back, as shown.

HUBERT J. BRAUN.
